(57) **CLAIM**

I claim the ornamental design for a bed, as shown and described.

DESCRIPTION

FIG. 1 is a front elevational view of the headboard portion of a bed according to an embodiment of the invention.

FIG. 2 is a front elevational view of the footboard portion of a bed according to an embodiment of the invention.

FIG. 3 is a side elevational view of a bed according to an embodiment of the invention. The view from the opposite side being a mirror image thereof.

FIG. 4 is a top plan view of a bed according to an embodiment of the invention; and,

FIG. 5 is a right front perspective view of a bed according to an embodiment of the invention.

The rear views of the headboard and footboard portions are not shown and form no part of the claimed design. The dashed lines represent environmental elements only and form no part of the claimed design.

1 Claim, 5 Drawing Sheets
